(57) **CLAIM**

The ornamental design for a portion of an IC card, as shown and described.

DESCRIPTION

FIG. 1 is a front, top and right side perspective view of a portion of an IC card, showing our new design;

FIG. 2 is a top plan view thereof;

FIG. 3 is a right side elevational view thereof; a left side elevational view being a mirror image thereof;

FIG. 4 a front elevational view thereof;

FIG. 5 is a rear elevational view thereof; and,

FIG. 6 is a bottom plan view thereof.

The broken line showing of the remaining parts of a portion of an IC card is for illustrative purposes only and forms no part of the claimed design.
